UNITED STATES PATENT OFFICE.

FRANK C. DE REAMER, OF SCHENECTADY, NEW YORK, ASSIGNOR TO
GENERAL ELECTRIC COMPANY, A CORPORATION OF NEW YORK.

ATTACHING PLUG AND RECEPTACLE.

No. 852,708.

Specification of Letters Patent.

Patented May 7, 1907.

Application filed October 31, 1904. Serial No. 230,683.

To all whom it may concern:

Be it known that I, FRANK C. DE REAMER, a citizen of the United States, residing at Schenectady, in the county of Schenectady 5 and State of New York, have invented certain new and useful Improvements in Attaching Plugs and Receptacles, of which the following is a specification.

The present invention relates to electric 10 distribution and more particularly to means for temporarily connecting a branch conductor in circuit with a main conductor.

Heretofore it has been customary to provide a receptacle having its contacts directly 15 engaging the main conductors and an attaching device having corresponding contacts in engagement with the branch conductors and adapted to be moved into and out of engagement by hand. These prior devices are ob- 20 jective for the reason that the circuit is made and broken by the engagement or disengagement of contacts, and because of the lack of a snap-action they soon become pitted and destroyed by the arcing action between 25 them.

The object of my invention is to provide a simple and compact attaching device for branch circuits which may be connected and disconnected without arcing between contacts, and a further object is to provide a de- 30 vice of this character which cannot be disconnected while current is passing in the branch conductor.

In carrying out my invention, I provide a 35 plug having a pair of contacts connected in the usual way to the ends of the branch conductor, and a receptacle having a corresponding pair of terminal contacts, a pair of binding posts for engaging the main conductor, a 40 snap-switch for electrically connecting one or both of the contacts with the respective binding post or posts, and a bolt or locking device adapted to engage a contact on the plug and controlled by the snap-switch.

The invention will be more readily understood by reference to the following detailed description and the accompanying drawing forming a part of this specification in which,

Figure 1 is an end elevation of an attaching 50 device embodying one form of my invention; Fig. 2 is a top plan of the receptacle with the face plate removed; and Fig. 3 is a longitudinal section of the receptacle on line 3-3 of Fig. 2.

The plug consists of an oblong knob 1 having a central cavity in which are arranged binding posts 2 for securing the ends of the branch conductors which are led through the top of the knob, and projecting from the lower end of the knob are two contacts 3 respectively connected at their upper ends with the binding posts and having ball-shaped extremities 4 split longitudinally to render them slightly yieldable.

The receptacle is designed to be secured in a recess in a wall and consists of a base 5 having end ears 6 for securing it in place and a face plate 7 adapted to be secured thereto and provided with bushed apertures 8 for the passage therethrough of the plug contacts 3 and an unbushed aperture 9 for the passage of the switch-actuating means.

The base 5 is of insulating material and in the form of a rectangular slab. At the left-hand end of the base two cylindrical cavities 75 10 are formed in which tubular contacts 11 12 are secured by screws 13 extending vertically through metallic connecting strips 14 and 15, and walls of the base and screw-threaded into the ends of the contacts. The 80 connecting strip 14 extends through a short channel in the lower side of the base to a screw 16 which connects it with a binding post 17 arranged in a depression 18 in the top side of the base and adapted to connect 85 with a main conductor wire adapted to be passed through a hole 19 extending through the base in proximity to the binding post. The other connecting strip 15 extends through a longer channel in the lower side of the base 90 to a screw 20 which connects it with a yoke piece 21. The yoke piece 21 is arranged in a depression in the top side of the base and consists of a metal punching with arms 22 bent up from opposite edges and apertured 95 to receive a locking bolt 23. The bolt 23 is provided with a round end 24 which extends through the side of tubular contact 12 and is yieldingly pressed into the path of one of the ball contacts 4 carried by the plug by a spring 25 surrounding the bolt and thrusting against an arm 22 and a collar 26 fixed to the bolt.

The snap-switch 27 is arranged in a recess 100 communicating with the recess in which the yoke piece 21 is arranged, and may be of any approved construction. The switch-blade 28 has its ends bent up parallel to the axis,

and the spring clips 29 30 are disposed on opposite sides in line with the locking bolt 23 so that when the switch-blade is in closed position it will engage the rear end of the 5 bolt and prevent its retraction while the switch remains closed.

The left-hand clip 29 is secured between the surface of the base and the under side of the yoke-piece 21, and the right-hand clip 30 10 is secured between the surface of the base and the bottom of the second binding post 31 located at the right-hand end of the main base cavity and adapted to engage a main conductor wire lead through a hole 32 in 15 proximity thereto.

I do not desire to restrict myself to the particular form or arrangement of parts herein described and shown, since it is apparent that they may be changed and modified without departing from my invention.

What I claim as new and desire to secure by Letters Patent of the United States, is,

1. The combination of an attaching plug, a receptacle therefor, means for locking said 25 plug in engagement with said receptacle, and a switch mounted on said receptacle and provided with a rotary contact adapted to close the circuit and secure said locking means.

2. The combination of an attaching plug,

a receptacle therefor provided with terminal contacts, a locking bolt with one end arranged in proximity to one of said terminal contacts, and a switch mounted on said receptacle and provided with a rotary contact 35 adapted to close the circuit and engage the opposite end of said bolt.

3. The combination of an attaching plug provided with independent contacts, a receptacle therefor having stationary contacts secured thereto, a spring pressed bolt arranged in line with one of the stationary contacts, and a rotary switch mounted in 40 said receptacle and adapted to abut against the end of said bolt.

4. The combination of an attaching plug having independent contacts with enlarged ends, a receptacle therefor having cup-shaped stationary contacts, a spring pressed bolt extending at one end through the side of a 50 stationary contact, and a rotary switch, adapted to engage the opposite end of said bolt and prevent retrograde movement thereof.

In witness whereof, I have hereunto set 55 my hand this 27th day of October, 1904.

FRANK C. DE REAMER.
